UNITED STATES PATENT OFFICE.

FREDERIC PAYSON REED, OF EAST ORANGE, NEW JERSEY, ASSIGNOR, BY MESNE
ASSIGNMENTS, TO CHARLES C. ORCUTT.

VACUUM POCKET.

Application filed February 7, 1921. Serial No. 443,008.

To all whom it may concern:

Be it known that I, FREDERIC PAYSON REED, a citizen of the United States, residing at East Orange, in the county of Essex, State of New Jersey, have invented certain new and useful improvements in Vacuum Pockets; and I do hereby declare the following to be a full, clear, and exact description of the invention, such as will enable others skilled in the art to which it appertains to make and use the same.

My invention is an improvement in paper coating machines, and relates especially to mechanism for use in connection with dryers for the paper, of the character shown and described in my prior application, Serial No. 434,231, filed December 31, 1920, for collecting and removing the vapor formed in the drying of the web.

20 An object of the invention is to provide mechanism of the character specified, adapted to be arranged beneath the web, within the casing of the dryer and near the point where the web leaves the dryer, for sucking up the vapor as it is formed and carrying it away from the dryer.

Another object is to provide means in connection with the said mechanism, for separating the air and vapor from the liquid 30 and delivering them from the dryer.

In the drawings:

Figure 1 is a longitudinal vertical section of a part of a dryer unit provided with the improved mechanism.

35 Figure 2 is an enlarged detail section of the said mechanism.

Figure 3 is a horizontal section at the end adjacent to the header.

In drying paper there is a large amount 40 of steam vapor formed, which tends to condense upon the drying web to again dampen the same, and to condense upon and within the dryer. This is especially true in dryers of the character above-mentioned, because 45 of the quick and thorough action of the units in removing the moisture from the paper web. To facilitate this dry action, by removing the vapors which would otherwise condense in part upon the web, I arrange 50 in each unit, or in any selected unit, the mechanism forming the subject-matter of the present invention. The said mechanism is shown in connection with a dryer unit, consisting of a casing 1 having an open 55 top, and having rollers 2 journaled at the

open top, over which passes one run of an endless belt or apron 3 of perforate material, for supporting the web 4 of paper. This belt or apron 3 is supported by rollers 5, in such manner that at the ends of the unit it may 60 pass beneath the casing 1 on the lower run of the apron. Electrically controlled heating units indicated at 6 are arranged within the casing, and the vapor removing mechanism is arranged at the dry end of the 65 unit, that is at that end towards which the paper web moves.

The mechanism comprises a pocket in the form of a casing 7 which is secured to an angle plate 8 arranged transversely of the 70 supporting frame 9 for the unit, and forming a part of the said frame. As shown in Figures 1 and 2, the casing 7 rests upon the horizontal portions of the angle plate, and is secured thereto by means of bolts and 75 nuts 10. A bar 11 is arranged within the casing 7 above the angle plate, and the bolts and nuts 10 clamp the bottom of the casing between the bar and the angle plate. The casing has a top 12 which is removably held 80 on the casing, by means of clamping bars 13 and 14. The bars 14 are arranged within the casing, beneath inturned flanges 15 on the side and end walls of the casing, and the clamping bars 13 and 14 are secured together 85 on the top by means of screws 16. A header 17 is arranged just outside the end wall of the casing, and a suitable pump is connected with one end of this header for making suction therethrough, and the header has a 90 series of radial nipples 18, each of which is flanged at its ends as shown at 19 in Figure 2. The nipples extend toward the casing 1, and the flanges of the nipples abut the end wall of the said casing. Short sections 95 20 of pipe, preferably of brass, are passed through registering openings in the rear wall of the casing 7 and in the end wall of the casing 1 and are threaded into the nipples. The casings 1 and 7 have registering 100 openings at each nipple 18, and a washer 21 is threaded onto the pipe 20 inside the casing 7. Thus the rear wall of the casing 7 and the end wall of the casing 1 are clamped between the washers 21 and the flanges 19 105 of the nipples 18. As shown in Figure 2, the pipes 20 extend to near the central vertical plane of the casing 7, and each pipe has a flaring mouth piece 22 at its inner end, the said mouthpieces being threaded 110

onto the pipes. A section 23 of pipe is passed through the front wall of the casing 7, the said wall having openings registering with the nipples 18, and a washer 24 is threaded onto this pipe section at the inner face of the front wall of the casing. A coupler or union 25 engages that end of the pipe 23 which extends beyond the front wall of the casing, and the said front wall 10 is thus clamped between the said washers 24 and the unions 25. A nozzle 26 is supported by the pipe sections 23, the said nozzle having extensions 27 in the form of threaded nipples, which engage within the unions. The nozzle has the opening thereof of just below the upper run of the apron 3, and it will be evident that when the air 15 is exhausted within the pocket or casing 7, air will be drawn in through the nozzle, and will carry with it vapor which is formed by the drying of the web. This vapor passes in through the pipe sections 23 to the pocket. The gas and vapor pass out through the pipe sections 20 to the header 25 or collector 17. The liquid passes down over the flaring surfaces of the mouth-pieces 22, onto the bottom of the casing 7, and means is provided for permitting the casing to be drained of such products. The 30 said means comprises a collector pipe 28 arranged beneath the casing 7, and connected to the casing at intervals by pipes 29. One end of the pipe 28 is closed, and valves 30 are arranged in the pipes 29 for 35 permitting the liquid contents of the pocket to be withdrawn when desired.

In a dryer unit provided with the improved vapor removing mechanism, all of the moisture vaporized by the action of the 40 dryer will be sucked into the pocket 7 through the nozzle, and the portion which condenses into liquid may be drawn off through the pipe 29. The gaseous portion passes out through the header 17. In the 45 usual arrangement, a portion of the vapor will re-condense upon the paper web, and this moisture must be removed throwing an additional burden on the heater if such moisture is afterwards removed, and producing an improperly dried paper if it is 50 not removed.

I claim:

1. In a dryer comprising a casing having a heater, and means for supporting a moving web of paper above the heater, of means 55 within the casing for collecting and removing the vapor formed in the drying of the web, said means comprising a suction nozzle arranged below the web, and extending 60 transversely thereof, a collector header, and a separating box between the suction nozzle and the collector header.

2. In a dryer comprising a casing having a heater, and means for supporting a moving web of paper above the heater, of means 65 within the casing for collecting and removing the vapor formed in the drying of the web, said means comprising a suction nozzle arranged below the web, and extending 70 transversely thereof, a collector header, and a separating box between the suction nozzle and the collector header, said box comprising a casing, pipes extending from the nozzle into the casing, and other pipes extending 75 from the header into the casing, and in alinement with the first-named pipes, and of a greater diameter, the ends of the first-named pipes extending into the ends of the last-named pipes.

3. In a dryer for paper or the like, means 80 for collecting and removing the vapor formed in the drying of the paper, and comprising a suction nozzle arranged adjacent to the paper, and extending transversely thereof.

4. In a dryer for paper or the like means for collecting and removing the vapor formed in the drying of the paper, and comprising a suction nozzle arranged adjacent to the paper, extending transversely thereof, 90 a collector header, and means for separating the air and vapor from the condensate connecting the nozzle with the header.

5. In a dryer for paper or the like means for collecting and removing the vapor 95 formed in the drying of the paper, and comprising a suction nozzle arranged adjacent to the paper, extending transversely thereof, a collector header, and a series of means for separating the air and vapor from the condensate connecting the nozzle with the 100 header.

6. In a dryer for paper or the like, a casing, means for supporting and guiding a web of paper or the like to be dried 105 through the casing, the top of the casing being open, and the web of paper closing the said top, heating means within the casing below the web, means for withdrawing air from the casing, said casing having inlet 110 openings through which air enters to replace that withdrawn.

7. In a dryer for paper or the like, a casing having an open top, means in connection with the casing for supporting a moving 115 web of paper or the like to be dried at the open top of the casing, heating means within the casing, and means for sucking the vapor caused by the drying of the web from the casing said casing having inlets for air 120 to replace that withdrawn.

In testimony whereof I affix my signature.

FREDERIC PAYSON REED.
